Wm Franklin Raigard

UNITED STATES PATENT OFFICE.

J. D. EVANS, OF PLEASANT HILL, GEORGIA.

IMPROVEMENT IN PLOWS.

Specification forming part of Letters Patent No. 69,083, dated September 24, 1867.

To all whom it may concern:

Be it known that I, J. D. EVANS, of Pleasant Hill, Talbotton P. O., Talbot county, State of Georgia, have invented new and useful Improvements in Plows; and I do hereby declare the following to be an exact description thereof, reference being had to the accompanying drawings, and to the letters of reference marked thereon, making a part of this specification, in which—

Figure 1 represents a side view of the plow; Fig. 2, a stay attached to the beam and foot-regulator; Fig. 3, a top view of the plow. Fig. 4 shows the construction of the foot regulator or support.

The nature of my invention consists in the construction of the foot support and regulator as an adjustable device, as combined with the foot-stay and beam.

A represents the foot or plow, that is pointed and curved in front and square at the top, with a bolt and nut, H, fastening it to the front of the regulator B, that is bolted and pivoted to the beam on each side of the beam

at E and E'. J is a connecting brace or stay, that is bolted at C to the center of the support or regulator B, and also to the beam at F, that is the pivoted brace for the regulator B, as the regulator B is adjusted to the required inclination by fastening the bolt C through the upper or lower apertures K K. The plow or foot A is adjusted higher or lower by means of the bolt and nut H, fitting between the sides of the regulator B, for the purpose of running the foot or plow A deep or shallow, according to the depth of furrow required.

What I claim as my invention, and desire to secure by Letters Patent, is—

The construction of the foot A and regulator B, as pivoted with bolts at C, and clamped on both sides of the beam D at E and E', when arranged and combined as herein described, and for the purposes set forth.

J. D. EVANS.
